UNITED STATES PATENT OFFICE.

JOSEPH J. SONSIKOWSKI AND JOHN K. SONSIKOWSKI, OF CHICAGO, ILLINOIS.

GAME OR TOY.

1,136,625.

Specification of Letters Patent.

Patented Apr. 20, 1915.

Application filed July 20, 1914. Serial No. 851,866.

To all whom it may concern:

Be it known that we, JOSEPH J. SONSIKOWSKI, a subject of the Emperor of Germany, and JOHN K. SONSIKOWSKI, a citizen 5 of the United States, both residing at Chicago, in the county of Cook and State of Illinois, have invented certain new and useful Improvements in Games or Toys, of which the following is a specification.

10 Our invention relates to games or toys and more particularly to games to be played upon a board or table by means of suitable devices or tokens, and capable of being played by an unlimited number of persons 15 from two to as many as may be able to group themselves around said board or table.

One of the objects of our invention is to construct a game that is capable of being continued when one or several persons withdraw 20 or "drop out" either temporarily or permanently, and to which any one or all of said withdrawn players may return and continue to play without affecting the relative status of any of the other players. Another 25 object is to construct a game of this character that will be interesting and instructive and afford opportunity for mental problems in the planning of attack or defense by the various players.

30 Still further objects are to provide a game apparatus that is easy to understand and play, simple in its construction and operation, and which is inexpensive to manufacture so that it may be sold for a reasonable 35 price by the retailer.

The above objects and others we prefer to accomplish by the means and in the manner hereinafter fully described and as more particularly pointed out in the claims, reference 40 being had to the accompanying drawings, forming a part of this specification, wherein similar reference characters indicate the same parts in the various figures.

45 In the drawings: Figure 1 is a perspective view of our game board showing several of the parts in their relative positions upon the same; Fig. 2 is a vertical section of a fragmentary portion of the board drawn to an enlarged scale and showing one of the counters or tokens in use; Fig. 3 is a top plan view 50 of our invention drawn to about the same scale as Fig. 1.

55 Referring to the drawings, 5 represents a suitable rectangular shaped base formed of wood, metal, fiber, or any other suitable ma-

terial, and which is preferably square or of equal dimensions upon its four sides, as shown. The upper surface of said base, preferably around the outer edges thereof, is provided with a half-round bead or molding 6 that surrounds the same and provides a suitable wall or edging to prevent the counters and other articles used in the game from slipping therefrom. Said board is provided with a plurality of equi-distantly spaced pins or pegs 7 that are inserted and secured in a corresponding number of holes or sockets 8 bored into the upper surface of said board. There are preferably ten rows of these pegs, each row containing ten pegs, 70 so that the pegs stand at the corners of eighty-one small squares that are formed thereby. It of course will be understood that any number of pegs or rows of pegs may be employed without departing from 75 the spirit of our invention, it being desirable, however, to employ enough pegs to form an odd number of squares in either direction, thus providing a square at the exact center of the board where an elongated 80 pin or pole 9 bearing a flag is removably mounted. Each of the above described pegs 7 is provided with four elongated slots or grooves 10 that extend longitudinally of each leg and parallel to each other and are 85 disposed upon the four quadrants of each peg, substantially as shown, with the grooves upon one peg facing and in alinement with the grooves upon the opposite pegs. Suitable plates 11 of substantially rectangular 90 shape are adapted to be inserted into the upper ends of the facing grooves of two pegs to form a wall between the same and a portion of the wall surrounding and enclosing each square as shown in Figs. 1 and 95 3 of the drawings, and when a player has completed a square wall he is permitted to place one of his counters or tokens 12 therein so that the particular square may be duly credited to him when the game is 100 finished.

In playing the game the counters or tokens 12 are sorted and distributed to the players so that each is provided with a number of the same color, indicia, or other means 105 of identification, and the square plates are all placed in a suitable receptacle. The object of the game is now to construct a wall around the block containing the flag and the player who in turn places the last plate 110

thereon wins the game. The game is played in rotation, each player endeavoring to construct walls with the plates around squares over the board and as soon as a square wall 5 is built the player completing said wall is privileged to place his counter therein whether he constructed the other three walls or not. Care, of course, is exercised by the players to avoid placing three of the wall 10 plates around the flag pole so as to prevent the succeeding player winning the game by placing the fourth wall thereon, and whenever a player completes a square and has placed his counter therein he is entitled to 15 another play. After the game has been won the proper credits are given the respective players according to the number of counters they have on the board, and then said board is inverted so that the wall plates will slide 20 out of their grooves in the pegs and the game may again be started.

In constructing the board we prefer to color the base and molding with red paint or stain, the pegs are colored white, and the square wall plates are colored blue, and the object of the game being to build a wall around and thus protect the flag adds a patriotic tone to the scheme of the game.

While we have herein shown and described certain specific means for carrying out our invention, it of course will be obvious to others skilled in the art to which it appertains that various changes or modifications thereof are possible, and we desire it understood that all such substitutions and refinements are contemplated within the

scope of our invention as set forth in the appended claims.

Having thus described our invention what we claim as new and desire to secure by Letters Patent, is:

1. A game apparatus comprising a suitable board, pegs arranged thereon and provided with longitudinal grooves, and devices adapted to be inserted longitudinally in 45 the grooves of two pegs to construct portions of figures.

2. A game apparatus comprising a suitable board, pegs arranged in rows thereon, and provided with longitudinal grooves, and 50 plates adapted to be inserted in facing grooves of said pegs.

3. A game apparatus comprising a suitable board, pegs arranged at the corners of geometric figures thereon, said pegs having 55 longitudinal grooves facing adjacent pegs, and plates adapted to be removably inserted in two of said grooves.

4. A game apparatus comprising a suitable board, equally spaced pegs arranged in 60 longitudinal and transverse alignment with each other, said pegs having longitudinal grooves facing adjacent pegs, and plates adapted to be removably inserted in two of 65 said grooves.

In testimony whereof we affix our signatures in the presence of two witnesses.

JOSEPH J. SONSIKOWSKI.
JOHN K. SONSIKOWSKI.
